2 SHEETS—SHEET 2.

UNITED STATES PATENT OFFICE.

EDWARD A. HENRICSON, OF CHICAGO, ILLINOIS.

SEAT INDICATOR FOR THEATERS.

1,425,255.

Specification of Letters Patent. Patented Aug. 8, 1922.

Application filed January 17, 1922. Serial No. 529,883.

To all whom it may concern:

Be it known that I, EDWARD A. HENRICSON, a citizen of the United States, residing at Chicago, in the county of Cook and State 5 of Illinois, have invented new and useful Improvements in Seat Indicators for Theaters, of which the following is a specification.

This invention relates to apparatus designed to be installed in theaters, moving picture houses, etc., for indicating the location of unoccupied chairs, to assist the ushers or patrons in finding such chairs, the invention being particularly useful where the 15 hall or other place in which the chairs are located is dark, as in moving picture theaters.

The invention has for its object to provide a simple and efficient indicating apparatus in which mechanical means alone are provided for accomplishing the result sought, no signal lamps or other devices requiring electric current being employed.

With the object stated in view, the invention consists in a novel combination and arrangement of parts to be hereinafter described and claimed, reference being had to the accompanying drawings, in which:

Figure 1 is a rear elevation of a row of 30 chairs, showing the application of the invention; Fig. 2 is a cross-section on the line 2-2 of Fig. 1; Fig. 3 is an enlarged vertical section of a seat-controlled mechanism; Fig. 4 is a sectional elevation of a fragment 35 of said mechanism, the section being taken on the line 4-4 of Fig. 3; Fig. 5 is an enlarged elevation of an indicator, partly in section; Fig. 6 is a vertical section on the line 6-6 of Fig. 1, and Fig. 7 is a diagram 40 showing a modification.

The drawings show a row of chairs to which the invention is applied. The seats of the chairs are shown at 10. It will be understood, of course, that each row of 45 chairs will be provided with the indicating apparatus which is the subject matter of the present application for patent. A row of five chairs is shown, but the apparatus is applicable to a row containing any other 50 number of chairs.

On the back of the row of seats 10 is mounted a channel bar 11, the same extend-

ing in the direction of the length of the row and being horizontally positioned, with its channel opening downwardly. In the channel are mounted pulleys 12 alternating with smaller pulleys 13 to guide a cable or other hauling line 14 extending from one end of the row of seats to the other, said cable being made fast at one end, and having at its 60 other end an operative connection with a rotatable indicator drum 15 to be presently described.

On one of the flanges of the bar 11 is mounted a pressed metal bracket 16 having horizontally projecting top and bottom wings 16^a which slidably support a spring-depressed plunger 17, the wings being perforated to receive the plunger. A plunger 17 is located back of each seat 10, 70 and to the latter is secured a lug 18 positioned to engage the bottom of the plunger and force the same upwardly against the tension of its spring 19 when the seat is swung down for occupancy, it being understood that the seat is pivoted as usual so that it may be swung down when it is to be occupied, and folded upwardly and back when not occupied.

The plunger 17 has a circumferential 80 groove 20 whereby it is connected to a slide consisting of an L-shaped plate, the two branches of which are shown at 21 and 22, branch 21 having a slot 23 to straddle the plunger at the groove. Branch 22 has a slot 24 through which passes a pin 25 which is secured by nuts 26, the slot permitting adjustment of the pin vertically, the branch 22 being vertically positioned, and the branch 21 being horizontal. One end of pin 25 90 passes through a vertical slot 27 in the adjacent flange of bar 11 and bracket 16 and supports a pulley 13, whereby said pulley is supported for a bodily vertical movement, it being understood that each of said pulleys is supported in this manner and provided with a seat-controlled actuator plunger 17.

At one end of the row of chairs is mounted a housing 28, the same being secured to 100 the end chair, and containing the rotatable indicator drum 15, the axis of which is vertical so that the inscriptions on its side may be displayed through a sight opening 29 in

the side of the housing. The housing 28 is closed at the top and open at the bottom. The drum 15 is open at the top and closed at the bottom, the latter seating on a pulley 30 from the top of which extends a spindle 31 which passes centrally through the drum and is fitted with a sleeve nut 32 for securing the drum to the pulley so that it may rotate with the latter.

- 10 The side or periphery of the drum 15 is divided into spaces numbering one more than the number of seats 10 in a row. As five seats are shown, numbers 1 to 5 are inscribed on the side of the drum with a luminous paint so as to be visible in the dark through the sight opening 29. The extra space is not inscribed as it indicates the fact that all the seats in the row are down and occupied.
- 15 20 The spindle 31 is supported by a shelf 33 mounted transversely in the housing 28 at the bottom thereof.

The line 14 is attached to and wound on the pulley 30, and when it is pulled, the pulley rotates in one direction and carries the drum 15 around with it. When the line is released, the pulley and the drum rotate in the opposite direction, this being effected by a coiled spring 34 secured at its upper end to the top of the housing 28, and at its lower end to the bottom of the drum.

The operation of the apparatus may be summarized as follows:

When all the seats 10 are occupied, the

- 35 lugs 18 are holding the plungers 17 pressed upwardly against the tension of their springs 19. The upward movement of the plungers when the seats were lowered for occupancy carried the pulleys 13 upwardly 40 to produce a slack in the line 14 which was taken up by the spring 34, turning the drum 15 and the pulley 30 in a direction to wind the line on said pulley, the drum thus turning to present the blank space 45 to the sight opening 29. If now one of the seats is swung upwardly as the occupant leaves the same, the lug 28 of the seat moves away from the lower end of the corresponding plunger 17, whereupon the latter is forced downwardly by its spring 19. The pulley 13 to which this plunger is connected moves downwardly with the latter, and thereby draws on the line 14 so that the drum 15 is rotated against the tension of 55 its spring 34, the movement of the drum being through an angular distance of one space, so that the inscription "1" is now displayed through the sight opening 29, if another seat is now emptied the drum is turned 60 to display the inscription "2," the same indicating that two seats in the row are empty, and so on, the inscription "5" being displayed when all the seats in the row are empty. As the seats are again occupied 65 the drum is rotated in a reverse direction by

the spring 34 as a slack is produced in the line 14 when the seats are lowered and the plungers 17 are forced upwardly and move the pulleys 13 in a corresponding direction to produce such slack.

As the housing 28 is positioned at the end of the row of seats, the sight opening 29 is visible from the aisle, and the usher can readily perceive the condition of the seats in the entire row. If the row contains a large number of seats, an indicator may be placed at each end of the row, one half of the seats controlling one indicator and the other half the other indicator. The apparatus may also be arranged to indicate the condition of the seats at each end of the row by duplicating the pulleys 12 and 13, and the cable 14, as well as the indicator drum 15 and associate parts, one drum being positioned at one end of the row and the other at the other end of the row. Fig. 7 shows this arrangement diagrammatically.

Figure 1 shows all the seats but one up or unoccupied, and in Fig. 2 the position of the parts when the seat is down is shown in full lines.

I claim:

1. The combination with a plurality of chairs having movable seats, of a rotatable indicator drum having its periphery divided into a number of characterized spaces and a blank space, and actuating means for the drum controlled by the seats for indicating the position of the latter.

2. The combination with a plurality of chairs having movable seats, of a rotatable indicator drum having its periphery divided into a number of characterized spaces and a blank space, and actuating means for the drum controlled by the seats for indicating the position of the latter, said actuating means moving the drum to display the blank space when all the seats are occupied.

3. The combination with a plurality of chairs having movable seats; of an indicator movable to denote the number of such seats in a predetermined position, a flexible member having an operative connection with the indicator for moving the same in one direction, means for moving the indicator in the opposite direction when a slack is produced in the flexible member, stationary and bodily movable pulleys over which the flexible member is trained, and means controlled by the seats for operating the movable pulleys to effect the tightening of and the slack in the flexible member.

4. The combination with a plurality of chairs having movable seats; of an indicator movable to denote the number of such seats in a predetermined position, a flexible member having an operative connection with the indicator for moving the same in one direction, means for moving the indicator in the opposite direction when a slack is produced in the flexible member, stationary and bodily movable pulleys over which the flexible member is trained, and means controlled by the seats for operating the movable pulleys to effect the tightening of and the slack in the flexible member.

slack is produced in the flexible member, stationary and bodily movable pulleys over which the flexible member is trained, slides carrying the movable pulleys, plungers having operative connections with the slides, and means on the seats for operating the plungers.

5. The combination with a plurality of chairs having movable seats; of an indicator movable to denote the number of such seats in a predetermined position, a flexible member having an operative connection with the indicator for moving the same in one direction, means for moving the indicator in the opposite direction when a slack is produced in the flexible member, stationary and bodily movable pulleys over which the flexible member is trained, slides carrying the movable pulleys, spring-pressed 10 plungers having operative connections with

the slides, and means on the seats for operating the plungers in one direction.

6. The combination with a plurality of chairs having movable seats; of an indicator movable to denote the number of such 25 seats in a predetermined position, a flexible member having an operative connection with the indicator for moving the same in one direction, means for moving the indicator in the opposite direction when a slack is produced in the flexible member, stationary and bodily movable pulleys over which the flexible member is trained, slides to which the movable pulleys are adjustably connected, plungers having operative connections with the slides, and means on the seats for operating the plungers.

In testimony whereof I affix my signature.

EDWARD A. HENRICSON.
